UNITED STATES PATENT OFFICE

2,591,412

LATERALLY MOVABLE CAR DOOR

Frank Ditchfield, Cleveland, Ohio, assignor to
The Youngstown Steel Door Company, Cleve-
land, Ohio, a corporation of Ohio

Original application August 11, 1945, Serial No.
610,315. Divided and this application Septem-
ber 24, 1947, Serial No. 775,785

4 Claims. (Cl. 20—23)

1

This invention relates to laterally movable car doors.

It is an object of this invention to provide laterally movable car doors which shall be readily operable from both the ground and platforms.

A further object is to provide laterally movable car doors which shall permit the application of a greater force to move the doors into and out of their door openings.

A further object is to provide laterally movable car doors which shall be supported upon bodily movable anti-friction means during movement toward and away from the cars and along door supporting tracks.

A further object is to provide laterally movable car doors embodying leverage means which shall automatically increase the effective force for moving the doors into their door openings as the doors approach their fully closed position.

A further object is to provide laterally movable car doors wherein the projection of the doors outwardly of the carside is reduced when the doors are in open position.

A further object is to provide laterally movable car doors which shall obtain a reduction in the length of door track.

A further object is to provide laterally movable car doors which shall be supported upon bodily movable anti-friction means during movement toward and away from the cars and along door supporting tracks wherein the anti-friction means shall be automatically positioned for proper rolling movement along the track.

A further object is to provide laterally movable car doors which shall be supported for movement upon freely rolling balls automatically disposed in proper position as the door is moved to closed position.

A further object is to provide laterally movable car doors operable toward and away from the car by mechanism embodying a horizontally disposed bar rotatably mounted on the doors and a transversely swingable handle swingable relative to the bar and adapted to be operatively connected thereto.

A further object is to provide laterally movable car doors operable toward and away from the car by mechanism embodying a horizontally disposed bar rotatably mounted on the doors and a transversely swingable handle wherein the mechanism is adapted to be locked by means associated with a handle in such manner that the locking means does not project outwardly beyond the handle.

A further object is to provide laterally movable car doors which shall require fewer parts, be sturdier in construction and more economical to manufacture.

Other objects of the invention will become clear as the description thereof proceeds.

2

In the drawings forming part of this specification:

Fig. 1 is a fragmentary elevation of a refrigerator carside equipped with a laterally movable door embodying the instant invention.

Fig. 2 is a vertical section taken on line 2—2 of Fig. 1.

Fig. 3 is a vertical section taken on line 3—3 of Fig. 1.

Fig. 4 is an enlarged elevation of a portion of the door and adjacent carside illustrating a portion of the mechanism for moving the door into and out of the door opening.

Fig. 5 is a horizontal section taken on line 5—5 of Fig. 4.

Fig. 6 is a vertical section taken on line 6—6 of Fig. 4.

Fig. 7 is an enlarged elevation of a portion of the operating handle and the shaft on which it is mounted, the handle being shown disengaged from the shaft in dot and dash lines.

Fig. 8 is a vertical section taken on line 8—8 of Fig. 7.

Fig. 9 is a vertical section taken on line 9—9 of Fig. 7.

Fig. 10 is a fragmentary enlarged elevation showing means for locking the lever.

Fig. 11 is an end view looking from the left in Fig. 10.

Fig. 12 is a horizontal section taken on line 12—12 of Fig. 1.

Fig. 13 is a vertical section taken on line 13—13 of Fig. 1.

For purposes of illustration the instant invention is shown applied to a laterally movable sliding door of a refrigerator car, it being understood, however, that the invention is not limited to these doors but is applicable as well to laterally movable sliding doors of box cars. The refrigerator car, which is designated in its entirety by the reference numeral 10, is of well known construction so that detailed description thereof is not necessary except insofar as it relates to the door and the operating and supporting mechanism therefor.

A door opening 11 is formed in each side of the car and is defined by means of front and rear door posts 12 and 13, a door header 14 and a sill 15. Within the door opening 11 a door 16 is adapted to be received and when in its fully closed position lies flush with the outer face of the carside wall as more clearly appears from Figs. 2, 3 and 5 of the drawings. It will be apparent that while the car and the door utilize wooden members in their construction, any other material, such as steel, may be employed if desired.

In order to assume the flush position within the door opening as illustrated in the drawings, and to assume the dot and dash line position

3

outwardly of the carside, as more clearly shown in Figs. 2 and 3 of the drawings, the door 16 is supported at its bottom edge by means of a plurality of balls 17 and 18 maintained in predetermined spaced relationship by means of a ball spacer 19. In its lateral movement into and out of the door opening 11, the balls ride upon a plate 20 mounted upon the sill 15 and upon a track 21 secured to the outer face of the sill 15. The track 21, moreover, supports the door for longitudinal movement upon the outside of the side wall when the door is opened and closed. During both the lateral and longitudinal movements of the door it will be apparent that the balls move bodily and in contact with the lower edge of the door which accordingly is reinforced by means of a substantially Z-shaped member 22 having a web 23 along which the balls move, an outer attaching upstanding flange 24 and a relatively short inner depending flange 25. The latter flange, as more clearly appears from Fig. 3 of the drawings, cooperates with a retaining plate 26 fastened as by means of welding to flange 24 to retain the balls and the spacer against lateral disengagement from the door. The depending flange 25 of the Z-shaped member 22 similarly cooperates with an upstanding flange 27 formed on the track for the same purpose when the door has been moved outwardly of the door opening.

The mechanism for accomplishing lateral movement of the door according to the instant invention embodies a horizontally disposed rectangular shaft or bar 28 mounted for rotation about its axis upon the door. For this purpose a plurality of brackets 29, 30 and 31 are fastened upon the door 16 and carry cylindrical bearings 32, 33, 34 and 35 within which the shaft is rotatable by means of bushings as indicated at 36, 37, 38 and 39 mounted upon the shaft and rotatable within the bearings.

Mounted on the ends of the shaft so as to rotate therewith and to lie beyond the vertical edges of the door are angular levers 40 and 41 which are similar in construction so that the description of the lever 40 will suffice for the description of the lever 41. Each of these levers, as more clearly appears in Fig. 6 of the drawings, embodies a relatively long arm 42 and a relatively short arm 43. The shaft 28 extends through a rectangular opening formed in the lever 40 in the angle formed by the arms 42 and 43 and the levers are retained upon the ends of the shaft by means of a plate member 44 riveted to the longer arm 42 as indicated at 45 and extending into a cope 46 formed in the shaft. A roller 47 is rotatably mounted upon the end of each of the arms 42 and a roller 48 is mounted upon the end of each of the arms 43.

In order to impart rotation to the shaft 28 a handle 49 is provided. At its upper end the handle is formed with a projecting flange 50 which is pivotally mounted in offset relationship to the axis of the handle between the jaws of a clevis 51 mounted upon the bushing 37 so as to be rotatable relative to the shaft. In order to connect the handle 49 to the shaft 28 in operative relationship therewith a clevis 52 is mounted upon the shaft 28 so as to be rotatable therewith. When in operative engagement with the shaft the upper end of handle 49 is disposed between the jaws 53 and 54 of clevis 52 so that movement of the handle transversely of the door will impart rotation to the shaft. Upon disengagement of the handle from the clevis 52 it will swing about

its pivotal connection with clevis 51 and be incapable of imparting rotation to the shaft.

Rotation of the shaft by means of handle 49 imparts rotation to the angular levers 40 and 41 which by their association with brackets 55 and 56 impart lateral movement to the door into or out of the door opening 11. These brackets, which are substantially similar in construction so that the description of one of them will be adequate for the other, are disposed within the door posts 12 and 13 so as to lie flush with the outer face of the posts and the carside.

Each of these brackets embodies a vertical inner wall 57 which, as more clearly shown in Fig. 6 of the drawings, is inclined outwardly from top to bottom. Attaching ears 58 and 59 extend above and below the wall 57 and provide means for securing the brackets to the door post as by means of bolts 60 and 61. Side walls 62 and 63 extend outwardly from the inner wall 57 and the side wall 63 is formed with a front wall 64 extending toward and terminating short of the side wall 62 as more clearly appears in Fig. 4 of the drawings. The latter wall is provided with attaching ears 65 and 66 through which bolts 67 and 68 are adapted to extend in order to fasten the brackets to the door posts. The side wall 62 is also provided with spaced parallel inclined walls 69 and 70 which, as more clearly shown in Fig. 6 of the drawings, are connected at their inner ends and provide an outwardly opening pocket in which a roller 43 is adapted to be received for a purpose hereinafter explained. As clearly appears from Fig. 6 of the drawings, the outer wall 64 terminates intermediate the ends of the inner wall 57 so as to provide openings 71 and 72 for a purpose which is later explained.

The door is shown in its fully closed position in Fig. 1 of the drawings. The position of the operating handle 49 when the door is closed is clearly shown in this figure and the relationship between the angular levers 40 and 41 and the brackets 55 and 56 is clearly shown in full lines in Fig. 6 of the drawings. In order to move the door so as to expose the door opening, lateral movement is first imparted thereto, this movement taking place upon the supporting balls 17 and 18. To impart lateral movement to the door the locking means for the locking handle, hereinafter described, is released and the handle, being disposed between the jaws of the clevis 52 and therefore in operative engagement with shaft 28, is swung upwardly in order to impart rotation to the shaft and through it to the angular levers 40 and 41.

During the initial rotation of the angular levers the rollers 47 on the shorter arms 43 bear against the lower inclined wall 70 and impart a thrust to the door, moving the latter outwardly from the door opening to the extent permitted by these arms. It will be apparent that by reason of the shortness of these arms a relatively large leverage is obtained for this portion of the lateral movement of the door so as to insure that the door will be disengaged from the packing or sealing means, which may be of any desired construction, secured around the door opening.

During the period in which the shorter arms 43 are effective the longer arms 42 are ineffective and merely rotate with the shaft so as to move the rollers 47 through the space 71 into engagement with the inner vertical wall 57. At this time the shorter arms have accomplished their purpose and continuing rotation of the shaft 28 by means of the operating handle 49 causes the

longer arms 42 to become effective and the rollers 47 to bear against and roll down the inner walls 57 in order to continue the outward lateral movement of the door.

During the effective period of the arms 42, the shorter arms 43 and the rollers 48 move outwardly from between the walls 69 and 70 and outwardly of the car wall. Finally, the rollers 47 are moved out of engagement with the brackets 55 and 56 through the space 72 and are disposed outwardly of the inner face of the door so as to avoid contact between them and the outer face of the carside as the door is moved longitudinally along the track.

When the door has been moved laterally to its fully outward position the operating handle 49 is disengaged from the jaws of the clevis 52 and permitted to swing upon its pivotal connection with the clevis 51 so as to assume the position shown in dot and dash lines in Fig. 7 of the drawings. This occurs because the clevis 51 will swing relative to the shaft 28 without imparting rotation thereto. In this manner the possibility of rotation of the shaft by means of the operating handle is eliminated, and damage to the handle if it remained in outwardly projecting position as a result of its engagement with the clevis 52 is avoided.

During its outward lateral movement the door as hereinafter explained is supported upon the balls 17 and 18. The upper edge of the door is guided outwardly during this movement by means of a plurality of angle guides 73-73, the horizontal leg 74 of which is fastened to the upper edge of the door as by means of screws 75. The upstanding leg 76 of each of the angle guides during this movement moves within slots 77 formed in the header 14. In this manner the upper edge of the door is properly guided both in its inward and outward movements in the door opening.

The outward movement is limited by engagement of the vertical flange 76 with the depending flange 79 of a substantially Z-shaped retaining bar 80 fastened to the outer face of the header 14. These flanges cooperate, moreover, in guiding the upper edge of the door during its longitudinal movement upon the track 21.

By reason of the fact that the door is supported upon the freely rolling balls 17 and 18 the invention permits the use of a supporting track which is substantially only one-half the length of track which would otherwise be required. As more clearly appears in Fig. 1 of the drawings, the track is not extended to the front door post 12 as is normally required but terminates substantially midway of the vertical edges of the door when the latter is closed. If desired, a small bracket 81 may be utilized at the lower front corner of the door in order to prevent possible teetering thereof when in closed position.

Similarly, the rear edge of the track does not extend substantially to the back stops 82 and 83 but terminates approximately midway between the vertical edges of the door when the latter is fully opened. If desired, a bracket 84 may be utilized at the lower rear corner of the door when open to prevent possible teetering thereof.

Moreover, the formation of the track is such that in cooperation with the door displacement of the balls 17 and 18 and the ball spacer 19 when the door is open or closed is avoided. For this purpose the ends of the track are flanged upwardly as indicated at 85 and 86 and the lower corners of the door are provided with depending flanges 87 and 88. As clearly appears from Fig. 1

of the drawings, when the door is fully closed the said end of the ball spacer lies adjacent to the upstanding flange 85 of the track which prevents movement of the spacer and the balls toward the left. At this time the depending flange 88 at the lower rear corner of the door lies adjacent to the ball spacer 19 and prevents movement thereof and the balls toward the right. Thus the balls and the spacer are fully confined and the balls will be immediately effective for rolling engagement with the door and the track when the door is opened.

Similarly, when the door is in full open position the rear end of the ball spacer 19 will lie adjacent to the upstanding track flange 86 and the forward end of the ball spacer will lie adjacent to the depending door flange 87 so that the spacer and the balls are again confined against movement relative to the door and track.

Means is also provided by the invention for insuring that the balls 17 and 18 will be properly aligned in parallel relationship to the outer face of the door when the door is in its fully closed position. For this purpose the side sill plate 20 is provided with a pair of upstanding lugs, one of which is indicated at 89. These lugs are so located upon the sill plate 20 that each of them lies adjacent to one of the balls 17 and 18 when the door is fully closed.

Thus when the door has been moved longitudinally upon the track 21 to a position overlying the door opening it is then forced laterally into the door opening by the mechanism above described. During this lateral movement of the door the balls and the spacer move laterally from the track 21 onto the sill plate 20. In the event that the ball spacer has become inclined relative to the outer face of the door during this movement so that the balls are not properly aligned, one end of the ball spacer will contact one of the lugs, such as 89, so that the lateral movement of this end and of the ball adjacent thereto will be arrested by the lug. Lateral movement of the other end of the spacer and of the other ball, however, will continue until the other end of the spacer is arrested by the other lug. At this time the balls are properly aligned.

To impart inward lateral movement to the door the operating handle 49 is swung together with the clevis 51 about the shaft 28 so that the handle may be disposed between the jaws of the clevis 52, thereby establishing operative engagement between the handle and the shaft 28. The handle 49 is then pulled downwardly and rotation is imparted to the shaft 28 and to the angular levers 40 and 41. This rotation of the angular levers causes the rollers 47 on the longer arms 42 to enter the brackets 55 and 56 through the space 72 between the lower end of walls 64 and the inner wall 57. Continued rotation of the shaft and the angular levers effects contact between the rollers 47 and the inner face of the walls 64, thereby forcing the door laterally into the door opening. During this movement a relatively small force is required inasmuch as the weight of the doors is supported upon the balls and the door has not as yet come into contact with the sealing means around the door opening.

Just prior to the time when contact between the door and the sealing means is established the rollers 48 engage the upper inclined wall 69 and the rollers 47 are disengaged from the walls 64. The force applied to the operating handle 49 is thereby transferred from the longer arms 42 to

the shorter arms 43 so that a far greater effective leverage for the final inward lateral movement of the door is obtained and the resistance offered to such movement by the compression of the backing material is easily overcome. During the final lateral movement of the door the rollers 47 pass outwardly through the space 11 so as to lie outwardly of the brackets 55 and 56.

The door is now in its fully closed position and locked therein by means so devised which does not increase the projection of the mechanism beyond the outer face of the door. This locking means which is shown in greater detail in Figs. 10 and 11 of the drawings embodies a bracket 90 fastened to the door and provided with outwardly extending spaced vertical lugs 91 and 92. The lug 92 carries a pair of spaced ears 93 and 94 between which one end of a locking member 95 is pivotally supported as by means of a rivet 96. The operating handle 49 is formed with an elongated slot 97 through which the locking member 95 is adapted to extend in order to fasten the handle to the door. The locking member 95 is adapted to be received within a bifurcation 98 formed in lug 91 and to be sealed to the bracket. For the latter purpose alined slots 99 and 100 are formed in the locking member and in a horizontally disposed lug 101 carried by the bracket lug 91. It is apparent from the foregoing that the locking means for the operating handle does not project outwardly beyond the outer face of the handle.

It will be observed from Fig. 3 of the drawings that when the door is closed the center of gravity of the door lies inwardly of the supporting balls 17 and 18 so the door is biased inwardly. Similarly, when the door has been moved out of the door opening, as shown in dot and dash lines in Fig. 3, its center of gravity lies outwardly of the balls so that the door is constantly biased away from the side wall of the car during its longitudinal movements along the track.

This application is a division of application Serial No. 610,315, filed by applicant on August 11, 1945, for Laterally Movable Car Doors, and now matured into Patent No. 2,560,419.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a railway house car embodying a wall provided with a door opening and having a header and a sill, a track carried by said sill, a door, balls supporting said door for transverse movement upon said track and said sill into and out of said door opening and for longitudinal movement upon said track, said balls rolling along said track and sill and along said door during said transverse movement of said door and along said track and door during said longitudinal movement of said door, transverse guide slots formed in said header, guide means secured to said door and slidable into and out of said slots, said guide slots and guide means cooperating to guide the upper edge of said door into and out of said door opening in substantially parallel relationship to said wall, and means secured to

said car, said latter means engaging said guide means to limit outward movement of said door.

2. In a railway house car embodying a wall provided with a door opening and having a sill, a track carried by said sill, a door, door supporting balls rolling along said track and sill and along said door for supporting said door for transverse movement into and out of said door opening and along said track and door for supporting said door for longitudinal movement, means spacing said balls, a member secured to said door in outwardly overlapping relationship with said ball spacer, and means secured to said sill inwardly of said member adapted to engage said ball spacer and properly dispose said balls when said door is being moved transversely into said door opening.

3. In a railway house car embodying a wall provided with a door opening and having a header and a sill, a track carried by said sill, a door, balls rolling along said track and sill and along said door for supporting said door for transverse movement into and out of said door opening and along said track and door for supporting said door for longitudinal movement, means spacing said balls, a member secured to said door in outwardly overlapping relationship with said ball spacer, transverse guide slots formed in said header, guide flanges secured to said door and slidable into and out of said slots, an upstanding flange on said track, a member secured to said header having a depending flange alined with said track flange, and a depending flange on said door, said flange on said second-mentioned member engaging said guide flanges and said track flange and door flange respectively engaging outer and inner portions of said ball spacer to limit outward movement of said door.

4. In a railway house car having a wall provided with a door opening, a door, a plurality of balls supporting said door on said car for transverse bodily movement into and out of said door opening, said balls rolling along said car and door during said movement, means for imparting said movement to said door upon said balls, said balls moving substantially to the outer plane of said door as said door moves transversely into said door opening and substantially to the inner plane of said door as said door moves transversely out of said door opening whereby the center of gravity of said door lies inwardly of said balls when said door is in said door opening and outwardly of said balls when said door is out of said door opening, and means on said car engaging and properly positioning said balls during transverse movement of said door into the door opening.
